UNITED STATES PATENT OFFICE

WILLIAM F. TAYLOR, OF LAFAYETTE, INDIANA

SINK

Application filed July 1, 1929. Serial No. 374,988.

This invention is a novel improvement in sheet metal sinks and its objects are to provide a sink which can be economically constructed with no rivets or fastening means showing on the interior of the sink, and in which the members of the sink are united outside the sink and form flanges by reinforcing ribs which imparts great rigidity to the sink, and having heavy fillets in the corners formed from the metal from which the body of the sink is made; all parts being so shaped that there will be no angles or corners in the sink in which dirt might accumulate; so that such sink can be easily cleaned.

I will explain the invention with reference to the accompanying drawings which illustrate several constructions of sink embodying the essential novel features of the invention. In the claims I have summarized the invention and the subordinate features thereof for which protection is desired.

In said drawings;

Fig. 1 is a perspective view of one set of members of the sink separated, and Fig. 2 shows such members assembled.

Fig. 3 is a perspective view of another set of sink members, separated, and Fig. 4 shows such members assembled.

Fig. 5 is a perspective view of another set of sink members separated, and Fig. 6 shows such members assembled.

Fig. 7 is an enlarged detail view of one of the reinforcing members 5.

Fig. 8 is an enlarged detail view showing how the corner fillets may be formed integral with the sink members.

As shown in Fig. 1 the back 1 and bottom 2 of the sink may be formed of one piece of sheet metal; the connecting portion or joint between the members 1 and 2 being curved as shown at 1f. The back 1 has a rearwardly projecting flange 1a at top, and rearwardly projecting flanges 1b, 1c at each side. The bottom 2 has depending flange 2a at its front edge and depending flanges 2b at its sides.

The front 3 and opposite sides 4 of the sink, as shown in Fig. 1 are formed of one piece of metal. The front 3 has a flange 3a on its lower edge which fits against the front flange 2a of the bottom; and each side mem-

ber 4 has a flange 4b on its lower edge adapted to fit against the adjacent side flange 2b of the bottom 2. Each side 4 also has an end flange 4c adapted to fit against the adjacent side flange 1c of the back 1.

When the parts are assembled as shown in Fig. 2 the meeting flanges 1c—4c; 2b—4b; 2a—3a, are rigidly united by rivets, or other suitable means, and are inseparable when united; and the flanges when thus united form a series of strengthening ribs on the exterior of the sink, see Fig. 2, which ribs impart great stiffness to the sink, and thoroughly reinforce it.

The corners of the sink are preferably formed by pressing the metal of the members into a parti-spherical shape as indicated at 3g, 4g. This may be done by removing surplus metal between the lines x—y as indicated in Fig. 8, and pressing the remaining parts in spherical contour and welding the line y between the adjacent sections of the metal, so that there will be no angles at the corners.

Any slight crevices or grooves that might be left at the bottoms of the curved portions 3e, 4e or at the upper edges of the junctions of the flanges 3a, 2a; 4b, 2b; 4c, 1c; can be filled with solder so that there will be no place within the sink where dirt can catch and accumulate.

The lower edge of the front 3 is inwardly curved as at 3e, and the lower edges of the sides 4 are inwardly curved as at 4e; also the adjacent ends of the sides 3 and 4 are connected by rounded portions or bends 3f; and the rear ends of the sides 4 adjacent flanges 4c are inwardly curved as at 4f; and all the corners are concaved or rounded as at 3g—4g, so that there are no sharp angles on the inside of the sink and no place for dirt to catch or accumulate.

Preferably the back 1 is widened above the sides 4, as shown, the part of the back projecting above the sides 4 being slightly wider than the part of the back intermediate such sides.

The flanges 1c are on the ends of the narrower portion of the back, and the flanges 1b on the edges of the wider portion of the back.

In order to strengthen the back and prevent

its bending between the adjacent ends of said flanges 1b, 1c I provide angle-iron reinforces 5 intermediate and connecting the adjacent ends of said flanges. Each reenforce 5 is preferably formed of sheet metal having offset upper and lower portions 5a and 5b connected by intermediate angle portions 5c. The portions 5a, 5b of the reinforcements are respectively fitted to the adjacent ends of the flanges 1b, 1c, behind the back, and riveted, or otherwise rigidly secured, thereto. Preferably the parts 5a, 5b, 5c of the reinforcing member are provided with stiffening flanges on their side edges as shown more clearly in Fig. 7.

15 The back is provided with suitable openings 1° and 1p for connection of faucets, etc. By having the drain opening 1° adjacent the back of the sink the chain (not shown) to which is attached the plug stopper (not shown) will always hang close to the back wall and be less liable to be caught by movement of articles being washed in the sink.

20 Preferably the bottom 2 is slightly depressed toward its rear end and center to direct water to the outlet opening 1° which may be connected with the drain pipe (not shown) in the usual manner, so that water will readily drain out of the sink.

25 The flange 1a is also preferably provided at center with a depressed pocket 1t. This depression can be used for retaining soap, scrub brushes, etc. which are customarily placed on the ledge formed by the top of the back wall. This depression can drain to the front of the splash-back.

30 If desired the upper edges of the front and side members of the sink can be finished in any other suitable way preferably with an integral bead or flange such as shown at 3t 35 in Figs. 1 to 4 or such a bead could be formed separately and secured thereto. Preferably I provide the upper edges of the side and front members with integral beads, such as 40 3t, to enhance the appearance of the sink and stiffen the upper edges of the front and sides thereof.

45 In the sink shown in Figs. 3 and 4, the back and bottom members are constructed as above 40 described, but the front and side members are formed separately. As shown the front 3x is provided with a flange 3i at each end; and each side 4x is provided with a flange 4i at its front end adapted to register with the adjacent flange 3i when the parts are assembled and the meeting flanges 3i, 4i are riveted or otherwise rigidly secured together. With the exceptions above noted the parts of the sink shown in Figs. 3 and 4 are constructed as 50 in Figs. 1 and 2, and similar parts are similarly lettered in the figures. The construction shown in Figs. 3 and 4 enables the front and sides to be made out of smaller sheets of metal than the construction shown in Figs. 1 and 2. Also the flanges 3i, 4i form addition-

55 al vertical strengthening ribs adjacent the front of the sink.

60 In the construction shown in Figs. 5 and 6, the back 1x is made separate from the bottom 2x. The front 3x is made as in Figs. 70 3 and 4, and the sides 4x are made integral with the bottom 2x and united therewith by bends 4n. The lower edge of the back 1x is also provided with a flange 1s, and the rear edge of the bottom 2 is provided with a 75 flange 2s which is riveted to the flange 1s when the parts are assembled. The flanges 2b, 4b (Figs. 1 and 2) are dispensed with, but the flanges 3i, 4i and 1c, 4c are retained. With these exceptions the bottom, back and sides 80 in Figs. 5 and 6 are formed as above described; similar parts being similarly lettered in the figures.

85 In my improved sink the various members are rigidly united by flanges riveted or otherwise secured together, but the fastenings between the sections are all outside of the sink, thus enhancing the sanitary value thereof; and such exterior flanges stiffen the sink and prevent deflection thereof when loaded.

90 The reinforces 5 overcome any tendency of the back to bend at the junction of the sides therewith and enhance the rigidity and durability of the structure.

95 The sinks are shown as mounted on tubular legs 6 having adjustable feet 6a; but any other suitable supports can be used. The adjustable feet allowing the sink to be readily levelled regardless of inequalities in the floor level.

100 The improved sinks are very sanitary owing to the absence of angles or corners where dirt might collect; all rivets are on the exterior of the sink; all seams are sweated with solder until extremely smooth; the location 105 of the drain makes for greater convenience in operation. The exterior flanges form ribs uniting the sink members and re-enforce the sink body and render it rigid and strong and the re-enforcements prevent the back bending 110 above the sides.

115 Each member of the sink has a curved junction of the sides with each adjacent member which curvature makes the sink easy to clean. The portion of the back projecting above the sides forms a protector or splash-back, and the flanges on the top and sides of the back form with the back and inclosure for the plumbing fixtures. All rivets being on the exterior of the sink the possibility of 120 collection of dirt at rivet edges is eliminated and by this construction there is no danger of shearing any rivets.

125 I claim:

1. A sheet metal sink comprising bottom, 125 back, front and side members all formed of sheet metal and secured together by abutting exterior flanges at the junctions of the meeting edges of the several separate members of the sink, a portion of the metal of one of the 130

- members adjacent each junction being rounded by curving the metal thereof and having a flange on the outer edge of such rounded portion, such flange lying in a plane parallel with but offset from the plane of the member on which such flange is formed, said exterior flanges when united forming stiffening ribs for the sink.
2. A sheet metal sink comprising back, bottom, front and side members all formed of sheet metal and secured together by abutting exterior flanges formed on the meeting edges of the several separate members of the sink, said exterior flanges when united forming stiffening ribs for the sink; the portion of the metal of one of the members adjacent each junction of the bottom with the back, front and sides, and of the sides with the back and front, being rounded by curving the metal thereof, and the flange on the rounded portion of a member being on the outer edge of such rounded portion and lying in a plane parallel with but offset from the plane of the member.
- 25 3. A sheet metal sink comprising bottom, back, front and side members all formed of sheet metal and secured together by abutting exterior flanges at the junctions of the meeting edges of the several separate members of the sink, a portion of the metal of one of the members adjacent each junction being rounded by curving the metal thereof, and having a flange on the outer edge of such rounded portion, such flange lying in a plane parallel with but offset from the plane of the member on which such flange is formed, said exterior flanges when united forming stiffening ribs for the sink; the back member of the sink extending above the side members thereof, and having its upper portion extended slightly beyond the side members and having rearwardly projecting side flanges on both its upper and lower portions, and reinforcing members connecting the upper and adjacent ends of the side flanges of the back.
